UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

PLAIT-FOLDER FOR SEWING-MACHINES.

1,236,684.

Specification of Letters Patent.

Patented Aug. 14, 1917.

Application filed April 9, 1913. Serial No. 759,826.

To all whom it may concern:

Be it known that I, ALBERT H. DE VOE, a citizen of the United States, residing at Westfield, in the county of Union and State 5 of New Jersey, have invented certain new and useful Improvements in Plait-Folders for Sewing-Machines, of which the following is a specification, reference being had therein to the accompanying drawings.

10 This invention relates to improvements in plait-folders for sewing machines, and has for its object to provide a device which may be readily adjusted to form box plaits of like and unlike widths at opposite sides of 15 the lines of stitching and conveniently adjusted for presenting the material to the action of the stitch-forming mechanism.

Referring to the drawings, Figure 1 is a view in perspective of the improved folding 20 attachment, together with so much of the bed-plate and the stitch-forming and cloth-feeding mechanism of the sewing machine as is deemed essential for a proper understanding of the invention; Fig. 2 a plan view 25 of the folding fingers and elements for effecting their adjustment, detached from the attachment base-plate; Fig. 3 an edge view of Fig. 2; Fig. 4 a plan view of the complementary folding blades and fold-guide detached from the sewing machine; Fig. 5 a cross-section on the line X—X, Fig. 1; Fig. 6 a cross-section on the line X'—X', Fig. 3; and Fig. 7 details, in perspective, later to be referred to.

30 Referring to the figures, 1 represents the bed-plate of the sewing machine, 2 and 3 the front and back slide plates, respectively, 4 the throat-plate, 5 the cloth-presser, 6 the cloth-presser bar, 7 the needle-bar with its 35 attached needles, as 8, 9 the feed-dog and 10 a portion of the head of the overhanging arm of the sewing machine.

11 represents a bracket secured to the head 10 by suitable screws, as 12 (one only 40 of which is shown), the lower arm 13 of said bracket being provided with adjustably secured plates, as 14, to the outer edges of which are secured by suitable screws, as 15, complementary folding blades 16 and 17, 45 screw 18 acting to secure said plates in their desired adjustment. 19 represents a fold-guide provided with an arm 20 adjustably secured in the bracket 11 by a screw 21.

22 represents the attachment base-plate 50 secured by screws, as 23, to the sewing ma-

chine bed-plate and at its fabric-receiving end provided with a tubular bearing 24 upon which is mounted an oscillating plait-fold-registering arm 26, secured against accidental movement by a screw 25 and washer 25', and an oscillating guiding and folding finger-adjusting lever 27, a spring washer 28 acting to resist slightly the movements of the lever 27, and a pinch collar 29 secured by screw 30 acting to hold the members 26, 27 and 28 against vertical movement on said tubular bearing. 31 represents a forwardly arranged folding and guiding finger-adjusting arm provided with a pin 32 and downwardly extended tubular bearing 33, and 34 a folding and guiding finger-adjusting arm provided with a downwardly extended bearing stud 35 and pin 36.

In assembling the parts 26 to 36, both inclusive, the parts 26, 27, 28 and 29 are arranged on the tubular bearing 24 in the order illustrated in Fig. 7, the tubular bearing 33 being mounted in the tubular bearing 24, and the lower end of the bearing 33 extending below the base-plate 22 a distance 50 sufficient to receive a second guiding and folding finger-adjusting lever 37, secured by screw 38 (shown in dotted lines only, Fig. 7), followed by positioning the bearing stud 35 in the tubular bearing 33, with its lower 55 end extending below the lower end of the bearing 33 a distance sufficient to receive the folding finger-adjusting lever 39 secured by screw 40, a pin 41 carried by an arm 42 of the adjusting lever 27 entering an opening 43 in the handle 44 of the lever 39, and a washer 45 secured on the pin 41 tracking the under side of the base-plate, it being understood that the levers 27 and 39 are arranged at the upper and under sides, respectively, 60 of the base-plate 22.

At the delivery end of the attachment, the base-plate is provided with a second tubular bearing 47 in which is mounted a tubular bearing 48 carrying at its upper end a folding and guiding finger-adjusting arm 49 provided with a pin 50, the bearing 48 having secured to its lower end, by screw 51, a crank-arm 52 whose outer end is pivotally connected to one end of a connection 53, the 65 opposite end of which latter is pivotally connected to an arm 54 carried by the adjusting lever 37.

55 represents a bearing stud mounted in the bearing 48 and carrying at its upper end 70

a folding and guiding finger-adjusting arm 56 provided with a pin 57, said bearing stud extending below the bearing 48 a distance sufficient to receive the crank-arm 58 secured by screw 59, the outer end of said crank-arm being pivotally connected to one end of a connection 60 whose opposite end is pivotally connected to the lever 39.

61 represents a left-hand and 62 a right-hand folding and guiding finger, each consisting of superposed plates 63 and 64 secured together by suitable screws, as 65, the guiding finger 61 being provided with slots 66 and 67 in which track the respective pins 36 and 57 and the finger 62 with like slots 68 and 69 in which track the respective pins 32 and 50. 70 and 71 are complementary swinging arms, each being pivoted at one end upon a stud 72 secured by screw 73 in the base-plate 22, their opposite ends 74 and 75 (shown in dotted lines only) being pivotally attached by pins 76 and 77 to the respective fingers 61 and 62, whereby said fingers are held against movement in the direction 25 of their length, the plates 64 being cut away to accommodate the relative action of said fingers and parts directly connected therewith. The guiding finger-adjusting arms 49 and 56 are preferably slightly longer than the arms 31 and 34, thus effecting adjustments of the fingers 61 and 62 at a slight angle to the line of seam formation.

From the foregoing it will be understood that the adjustment of the finger 61 is effected through the manipulation of the handle 44 connected with the pins 36 and 57 through the elements 34, 35, 39, 60, 58, 55 and 56, and that the adjustment of the finger 62 is effected through the manipulation of the lever 37 connected with the pins 32 and 50 through the elements 31, 33, 38, 54, 53, 52, 48 and 49, each finger being thus independently controlled to form plaits of like and unlike widths at opposite sides of the lines of stitching.

An adjustment of the parts as shown in Fig. 1 would effect a plait of substantially one and three-quarter inches in width, the narrower plaits being gaged by adjusting the registering arm 26 in the direction indicated by the arrow *t*, and the wider plaits by adjusting said arm in the opposite direction; but when it is desired to effect a fold wider at one side of the stitching than at the other, 55 either the lever 27 or 37, depending upon the side of the stitching at which the narrower fold is to be formed, is moved away from the arm 26 to the point of the index *b* indicating the desired width of fold.

60 In forming box-plaits as herein pointed out, it is quite frequently necessary to adjust the fabric under the needle after the commencement of the stitching operation, as when one seam has been advanced beyond 65 the other through the accidental breaking of

one of the sewing threads; and when making such adjustment it is desirable to release the fabric by moving one of the folding and guiding fingers, in the present construction the finger 61, toward the needles, the return movement of said finger to its given adjustment being controlled by the arm 26, thus effecting relative adjustments of the folding and guiding fingers into and out of given adjustments without disarranging the fabric 75 or consulting the index.

The dotted lines A—A, Fig. 5, represent the lines of stitching.

Having thus set forth the nature of the invention, what I claim herein is:—

1. In a box-plait folder for sewing machines, the combination with oppositely arranged folding blades suspended above the sewing machine bed-plate, adjustably secured complementary folding and guiding fingers cooperating with said folding blades to form a box-plait and means for effecting relative adjustments of said fingers to form a given width of plait of an adjustably secured plait-fold registering member against which said means for effecting relative adjustment of the fingers may be brought in contact for restoring the relative adjustment of said fingers when, for any purpose, their relationship for effecting said given 90 width of plait has been disturbed.

2. In a box-plait folder for sewing machines, the combination with oppositely arranged folding blades suspended above the sewing machine bed-plate, adjustably secured complementary folding and guiding fingers cooperating with said folding blades to form a box-plait and means for effecting relative adjustments of said fingers to form a given width of plait having a different width of fold at one than at the opposite side of the lines of seam formation, of an adjustably secured plait-fold registering member against which said means for effecting relative adjustment of the fingers may be brought in contact for restoring the relative adjustment of said fingers when, for any purpose, their relationship for effecting said given width has been disturbed.

3. In a box-plait folder for sewing machines, the combination with oppositely arranged folding blades suspended above the sewing machine bed-plate, adjustably secured complementary folding and guiding fingers one of which is adjustable independently of its coacting fingers, said fingers cooperating with said folding blades to form a box-plait and means for effecting relative adjustments of said fingers to form a given width of plait, of an adjustably secured plait-fold registering member against which said means for effecting relative adjustment of the fingers may be brought in contact for restoring the relative adjustment of said fingers when, for any purpose, their rela- 130

tionship for effecting said given width of plait has been disturbed.

4. In a box-plait folder for sewing machines, the combination with a bracket provided with oppositely arranged folding blades suspended above the sewing machine bed-plate, adjustably secured complementary folding and guiding fingers one of which is adjustable independently of its coating finger, said fingers coöperating with said folding blades to form a box-plait and means for effecting relative adjustments of said fingers to form a given width of plait, of an adjustably secured plait-fold registering

member against which said means for effecting relative adjustment of the fingers may be brought in contact for restoring the relative adjustment of said fingers when, for any purpose, their relationship for effecting said given width of plait has been disturbed. 15 20

In testimony whereof, I have signed my name to this specification, in the presence of two subscribing witnesses.

ALBERT H. DE VOE.
